UNITED STATES PATENT OFFICE

EDWARD J. GULICK, OF ELKHART, INDIANA, ASSIGNOR TO C. G. CONN, LTD., OF
ELKHART, INDIANA, A CORPORATION OF INDIANA

TUNING-SLIDE-ACTUATING MECHANISM

Application filed July 19, 1928. Serial No. 293,896.

This invention relates to wind musical instruments and particularly tuning slide mechanism for horns.

The principal object of my invention is to provide a tuning slide for horns, and the like, which is readily actuated by one finger of the player's hand which supports the instrument.

Another object of the invention is to provide a spring retracted tuning slide for horns, and the like, which is readily actuated by the player to lower or modify the tone of the instrument.

Other objects of the invention are mentioned and described herein.

The preferred embodiment of my invention is illustrated in the accompanying drawings, wherein

Figure 1 illustrates a side view of a cornet to which my invention is applied;

Fig. 2 is a section taken on line 2—2 of Fig. 1;

Fig. 3 illustrates an enlarged fragment of the instrument in which my invention is incorporated, the view being taken from the side opposite to that shown in Fig. 1;

Fig. 4 is a section taken on line 4—4 of Fig. 1; and

Fig. 5 is a section taken on line 5—5 of Fig. 1.

Similar numerals of reference indicate like parts throughout the several views on the drawings.

Referring to the details of the drawing the numeral 1 represents a common type of cornet which is provided with the stationary parallel tubes 2 and 3 which are open at their outer ends to telescopically receive the tubes 5 and 6 of the U shaped tuning slide 4. Normally the slide 4 is held retracted by a coil spring 19 to cause the shoulders 7 and 8 of the slide 4 and tube 3, respectively, to engage. To modify the tone of the instrument the slide 4 is outwardly projected (Fig. 3) by the lever 9 which is pivotally mounted intermediate its extremities on the bearing pin 10 which has its inner end screw threaded into a block 11 rigidly secured to the tube 2. The outer end of the bearing pin 10 may penetrate and be somewhat supported by a block 12 rigid

with the under surface of a tube 13 positioned adjacent the tubes 2 and 3.

The lower end of the lever 9 is provided with a ring-like handle 14 adapted to be engaged by a finger of one hand of the player, and the upper or opposite end of said lever is connected with a link 15 which extends forwardly to the pivot screw 16 threaded into a post 17 which is rigidly mounted between the tubes 5 and 6 of the slide 4. A pivot screw 18 which is threaded into the opposite end of the link 15 operatively connects said link with the upper end of the lever 9.

The coil tension spring 19 encompasses a portion of the rod 20 which has its outer end rigidly connected with the extension 21 of the post 17, said rod being slidably mounted in an aperture 22 formed in a post 23 which is rigidly mounted between the tubes 2 and 3. The coil spring 19 has end hooks 24 and 25, respectively, connected with the posts 23 and 21, respectively, for anchorage purposes. A pair of nuts 26 and 27 are threaded upon the threads 28 formed adjacent one extremity of the rod 20, nut 26 normally bearing against the post 23 to limit the outward movement of the slide 4.

The nut 27 may function as a lock nut for the stop nut 26, to preserve the adjustment of the latter, and the latter may be adjusted back and forth on the rod 20 to regulate the extent of outward movement of the slide 4, and thereby the tension of spring 19. Preferably the lever 9 is so placed in relation to the valve casings A, B, and C of the instrument that it is readily accessible to the player's hand, or one of the fingers thereof, which is grasping said valve casings, and to operate the slide 4 the player may readily engage the ring-like handle 14 with the fourth finger of his hand without in any degree impairing his grasp on the instrument with the remaining fingers and thumb of the same hand.

The post 23 may be similar in construction to the post extension 21 to enable the ready connection of the spring hook 24 therewith.

Obviously, oscillation of the lever 9 will actuate the slide 4 outwardly until the stop nut 26 engages the post 23, whereby the instrument tone is modified or lowered. Upon

release of the handle 14 the slide 4 is instantly retracted by the spring 19 to its former and normal position.

I claim:—

- 5 1. In a wind musical instrument of the character described, the combination of a movable tuning slide, of a rod rigidly connected with the slide and slidably connected with the body of the instrument, a tension spring for retracting the slide, an adjustable stop element on said rod for limiting the movement of the slide, and lever and link mechanism for actuating said slide against said spring.
- 10 2. In a wind musical instrument of the character described the combination with a U shaped tuning slide and the stationary tubes with which the slide telescopes, of means for manually outwardly actuating the tuning slide, spring means for retracting the slide, and adjustable stop means for limiting the outward movement of said slide, said means including a rod rigidly connected with the tuning slide between the tubes thereof and disposed substantially parallel therewith, an apertured anchorage post rigidly mounted between said instrument stationary tubes, the aperture whereof is slidably traversed by said rod, and a stop nut screw 25 threaded upon said rod and adapted to engage said anchorage post upon outward movement of the tuning slide.
3. In a wind musical instrument of the character described the combination with a U shaped tuning slide and the stationary tubes with which the slide telescopes, of means for manually outwardly actuating the tuning slide, said means including an anchorage element mounted between the slide tubes, 30 spring means connected with said anchorage element for retracting the tuning slide, and adjustable stop means for limiting the outward movement of said slide, said means including a rod rigidly connected with said 35 slide anchorage element and arranged substantially parallel with the slide tubes, an apertured anchorage post rigidly mounted between said instrument stationary tubes, the aperture whereof is slidably traversed by 40 said rod, said retracting spring being anchored to said anchorage post, and a stop nut screw threaded to said rod and adapted to engage said anchorage post upon outward movement of said slide.
- 45 4. In a wind musical instrument of the character described, the combination of a movable tuning slide, lever and linkage means for outwardly actuating the slide, a spring for retracting the slide, and screw means for adjusting the tension of said spring.
- 50 5. In a wind musical instrument of the character described, the combination of a U shaped tuning slide, the stationary instrument tubes with which the tuning slide

telescopically cooperates, means for manually and outwardly actuating the tuning slide, spring means for retracting the tuning slide, and screw means mounted adjacent said instrument tubes for adjusting the tension of said spring.

EDWARD J. GULICK.
